(57) **CLAIM**

The ornamental design for a valve cover for internal combustion engine, as shown and described.

DESCRIPTION

FIG. 1 is front perspective view of a valve cover for internal combustion engine according to the present invention; FIG. 2 is a rear perspective view of the valve cover for internal combustion engine; FIG. 3 is a front elevation view of the valve cover for internal combustion engine; FIG. 4 is a rear elevation view of the valve cover for internal combustion engine; FIG. 5 is a right side elevation view of the valve cover for internal combustion engine, the left side elevation being a mirror image thereof; FIG. 6 is a top plan view of the valve cover for internal combustion engine; and, FIG. 7 is a bottom plan view of the valve cover for internal combustion engine. The broken lines in the drawings illustrate portions of the valve cover for internal combustion engine that form no part of the patented design.
